US00D944475S

(12) **United States Design Patent** (10) **Patent No.:** **US D944,475 S**
(45) **Date of Patent:** **** Feb. 22, 2022**

(54) **HAND VACUUM CLEANER**

(71) Applicant: **SharkNinja Operating, LLC**,
Needham, MA (US)

(72) Inventors: **Scott B. Niedzwecki**, East Walpole,
MA (US); **Junghwan Chei**, Chestnut
Hill, MA (US)

(73) Assignee: **SHARKNINJA OPERATING LLC**,
Needham, MA (US)

(**) Term: **15 Years**

(21) Appl. No.: **29/669,500**

(22) Filed: **Nov. 8, 2018**

(51) LOC (13) Cl. **15-05**

(52) U.S. Cl.
USPC **D32/18**

(58) **Field of Classification Search**

(57) **CLAIM**

The ornamental design for a hand vacuum cleaner, as shown and described.

DESCRIPTION

FIG. 1 is a front, top, left perspective view of a hand vacuum cleaner, showing a new design;

FIG. 2 is a front, top, right perspective view thereof;

FIG. 3 is a rear, top, left perspective view thereof;

FIG. 4 is a rear, top, right perspective view thereof;

FIG. 5 is a rear, bottom, left perspective view thereof;

FIG. 6 is a rear, bottom, right perspective view thereof;

FIG. 7 is a front, bottom, right perspective view thereof;

FIG. 8 is a front, bottom, left perspective view thereof;

FIG. 9 is a top view thereof;

FIG. 10 is a bottom view thereof;

FIG. 11 is a left view thereof;

FIG. 12 is a right view thereof;

FIG. 13 is a rear view thereof; and,

FIG. 14 is a front view thereof.

The broken lines shown in the hand vacuum cleaner are for portions that forms no part of the claimed design.

1 Claim, 13 Drawing Sheets
